UNITED STATES PATENT OFFICE.

FRANK M. GREENE, OF MINNEAPOLIS, MINNESOTA.

ENGINEER'S CAB-SIGNAL.

1,229,178.

Specification of Letters Patent. Patented June 5, 1917.

Application filed April 15, 1914. Serial No. 881,952.

To all whom it may concern:

Be it known that I, FRANK M. GREENE, a citizen of the United States, resident of Minneapolis, Hennepin county, Minnesota, 5 have invented certain new and useful Improvements in Engineers' Cab-Signals, of which the following is a specification.

The object of my invention is to provide a signal adapted for use on a locomotive for 10 the purpose of indicating to the engineer if the track is clear, or if caution should be exercised, or operating under certain conditions to release the air from the brake cylinders and set the brakes.

15 The invention consists generally in various constructions and combinations, all as hereinafter described and particularly pointed out in the claims.

In the accompanying drawings forming 20 part of this specification,

Figure 1 is an elevation illustrating the manner of supporting the signal device by the track and its position with respect to the engineer's cab,

25 Fig. 2 is a detail sectional view, showing the connection with the signaling mechanism in the cab,

Fig. 3 is a perspective view, showing the means for mounting the signal actuating device on the posts at the side of the track,

30 Fig. 4 is a detail sectional view of the controlling valve,

In the drawing, 2 represents a railway track of ordinary construction, 3 a locomotive having a cab 4 thereon of ordinary construction, and 5 represent posts mounted on each side of the track. 6 is a rod, which may be connected to the operating mechanism of a semaphore to be operated simultaneously therewith. Bell cranks 7 are pivoted at 8 and have one arm attached to the rod 6 and the other to rods 9 which extend upwardly opposite the posts 5 and are pivotally connected to levers 10 which in turn are pivoted at 11 on the upper ends of the posts and have short arms carrying weights 12 and long arms for supporting a wire 13 which extends over the track and has yielding connections, such as springs 14, with 45 the levers 10. This wire forms the actuating means of the signal device.

Mounted on the top of the cab is a bar 15, preferably formed in two sections, pivoted at 16 on the cab and normally held in its 50 raised position by a spring 17 and adapted to swing in a guide 18 having a yielding

stop 19. A bar 20 is adapted to slide in a guide 15. A series of dogs 21, 22 and 23 are pivoted at one end on the guide 15 and the dogs 21 and 22 have pivotal sliding connections with the bar 20, by means of slots 24 and 25 therein. The dog 23 has a pivotal, non-sliding connection 26 with the bar 20.

The dogs project beyond the bar 20 on one side and are adapted to swing upward 65 when struck by an object in the path of the dogs. The lower end of the bar 20 is pivotally connected to a link 27, that is attached at one end to a crank 28 that is mounted on a valve 29 provided with a port 70

30 therein. A spring 31 normally holds this valve in its closed position and cuts off the flow of air through the pipe 32 to the whistle 33. When the valve is moved a short distance, a small volume of air will pass 75 through the valve to the whistle, which volume will be increased as the valve is opened wider, until the whistle is being blown at its fullest extent. This sound of the whistle is utilized in signaling the engineer, assuming that the semaphore is set for a clear track.

80 The wire 13 will be dropped down to a point where it will engage with the dog 21, the movement of the parts being so timed that this dog will swing and move the bar 20 a short distance, sufficient, however, to partially open the valve 29 and allow air to flow to the whistle, the sound of the whistle indicating to the engineer that the track is clear.

If the actuating wire 13 should be 90 dropped down lower by the movement of the semaphore, where it will operate the dog 22, then the valve 29 will be opened a greater distance and a larger volume of air will flow to the whistle and a louder signal 95 will be sounded, and when the operating wire is dropped down to a point where it will engage with the dog 23, the valve will be thrown wide open and the air will be released from the train pipe to the brake cylinders sufficient to automatically set the 100 brakes. The second signal will be generally utilized to indicate caution, and warn the engineer that there is danger ahead, while the third signal is a positive indication of danger and through the automatic setting of the brakes the engineer will be 105 positively prevented from going ahead with his train, or running by the danger signal of the semaphore.

110 In various ways the details of construction herein shown and described may be

modified and still be within the scope of my invention.

I claim as my invention:

- 5 1. The combination, with an engineer's cab and a signaling device mounted therein, of means mounted on said cab and operatively connected with said signaling device, said means comprising members to be actuated for indicating a clear track, caution or danger, and a device extending over the track and beneath which the cab passes and capable of adjustment for actuating certain of said members for sounding the desired signal in the cab.
- 10 15 2. The combination, with a cab, of a fluid pressure operated signal therein, and a valve for controlling the passage of the fluid pressure to said signal, a sliding member projecting above said cab and operatively connected with said valve to open the same, a series of pivoted dogs connected with said member, the movement of one of said dogs opening said valve a predetermined distance to indicate caution and the other dog opening the valve a greater distance to indicate danger, and means supported above the track and extending across the same and adapted to be moved into the path of said dogs respectively for actuating the same.
- 20 25 3. A signaling device comprising means supported above the track and operated by the setting of a visual signal, in combination with a signaling device in the engineer's cab, and mechanism operatively connected with said signaling device and projecting above the cab to be positively actuated by said visual signal operated means, said mechanism including devices operable independently of one another for operating a predetermined signal. 40
4. A railway signal comprising an actuating element supported above the track for movement from an inoperative to an operative position, an engineer's signaling device mounted in the cab, a releasing mechanism connected therewith comprising members to be actuated for indicating a clear track, caution, or danger, and arranged to pass beneath said actuating element to be operated selectively through the adjustment of said actuating element for sounding the desired signal in the cab. 45

In witness whereof, I have hereunto set my hand this 28th day of March, 1914.

FRANK M. GREENE.
